FUR SLITTING DEVICE

Samuel Deutscher, Brooklyn, N. Y.

Application March 14, 1940, Serial No. 323,885

11 Claims. (Cl. 164—73)

My invention relates to fur slitting devices and has particular reference to devices for slitting or cutting furs into narrow strips for the preparation of matched fur covering for articles of wearing apparel.

In the preparation of coats and similar articles of wearing apparel from high-priced furs such as mink, etc., the individual pelts are cut into narrow strips, usually about one-eighth of an 10 inch wide, preferably on bias, and such strips are sewed together again, shifting every strip in relation to the other so as to produce a relatively long and narrow piece of fur. This operation is called "let out" and "reset" in the 15 fur trade.

The slitting operation is usually performed by hand, cutting one strip at a time, using special thin knives, preferably made of razor blades held in special flat holders. Such an operation requires considerable skill, is very slow, and, therefore, considerably adds to the cost of the product.

My invention has for its object to provide means for cutting simultaneously a large number of narrow strips from a pelt at an angle, thereby insuring accuracy of the work and uniformity of the strips. I provide for this purpose a more or less large number of thin knives removably supported on an elongated holder which 30 can be held in a hand while applying the knives to a pelt in a desired direction.

The pelts, such as mink, are usually cut on a bias or in an angular direction for "let out" and "reset" cutting, to the right or to the left, and, occasionally, straight across. Another object of 35 my invention is therefore to provide means for mounting the knives on my holder in an angular position, to the right or to the left, as desired, or at right angles to the holder.

Another object of my invention is to provide a holder for the knives in the form of an elongated box with a removable drawer in which 40 spare knives and knife holders can be kept until needed.

Another object of my invention is to provide a supporting and stretching frame for pelts so as to facilitate the slitting operation. I also provide a guiding rail above the frame, the knife 45 holder having an angular member which can engage the rail so that the holder with the knives can be moved along the rail over the pelt in a fixed angular direction, thereby slitting the fur in the exact angular direction.

I also provide a scale at one side of the box

or knife holder for convenience in measuring the strips of pelts.

In a modified form of my invention I employ an electric motor or other suitable source of power including a manually operable pedal, for moving the holder with the knives, a suitable switching device being provided for controlling the motor.

My invention is more fully described in the accompanying specification and drawings in 10 which—

Fig. 1 is a top plan view of my device partly in section;

Fig. 2 is a front view of the same partly in section;

Fig. 3 is a sectional end view of the same partly in section;

Fig. 4 is a detail view of a knife holder with a knife;

Fig. 5 is a top view of the same;

20

Fig. 6 is an end view of the same;

Fig. 7 is a detail view of a retaining plate for the knife;

Fig. 8 is a perspective view of a fur supporting frame with a slitting device;

25

Fig. 9 is a fractional detail view of clamping bars for the furs;

Fig. 10 is a fractional top plan view of the same;

Fig. 11 is an elevational view of a modified device employing an electric motor.

My fur slitting device consists of an elongated holder in the form of a box 1 with a drawer 2 which is used for keeping spare parts. The top board 4 of the box has a row of metal inserts 35

5 threaded for screws 6, which support knife holders 7. The inserts are placed at a short distance apart, preferably about one-eighth of an inch, so that the knife holders, if placed at right angles to the box as shown in dotted lines 7' 40

in Fig. 1, will be also one-eighth of an inch apart. Usually, however, the knives are placed at an angle for cutting the fur at a bias, the angle being preferably 15° as shown in Fig. 1. The

knives will be then also one-eighth of an inch 45 apart if the ends of the holders are mounted on every fourth insert 5. It is evident, therefore,

that with such an angular arrangement, only one fourth as many knives can be placed on the box as with the knives extending at right angles. 50

The knife holders are held in the angular position by lugs or dowels 8, Fig. 4, fitting in corresponding holes 9 in the board 4. The holes extend to the left on the board 4 as shown in Fig. 1,

so that the knives can be turned over to the left 55

into a position indicated in dotted lines 7' at the left in Fig. 1. A corresponding row of holes 9' is provided at the edge of the board 4 for the position of the knives shown in dotted lines 7'.

5 The knives are held tight against the board 4 by a bar 10 extending over the upper edges of the knife holders and fastened at the ends by screws 11 threaded into posts 12.

The front side of the drawer 2 is inclined as shown and provided with divisions 13 for measuring the length of different portions of the work. The rear wall of the drawer is relatively low, consisting of portions 14 and 15 of different height, comb teeth 16 and 17 being inserted 15 into the edges of these portions. The drawer therefore can be used as a comb for straightening out the fur, different portions 14 and 15 being used for furs with different length of hair.

The drawer 2 is used for keeping spare knife 20 holders 7 at the right and left end portions, the holders being stacked and clamped together and against the bottom of the drawer by bars 18 rotatively supported on studs 19 and tightened by wing nuts 20. Walls 21 extend from the rear 25 walls 14 and 15 and form an inner compartment 22 for storing knife blades 23. The latter are preferably made of ordinary safety razor blades by breaking them diagonally as shown. They are also stacked and clamped by bars or plates 30 24 on studs 25 and tightened by nuts 26. The left portion of the compartment 22 may be reserved for complete razor blades also held in place by suitable nuts and studs.

The knife holder is shown in detail in Figs. 4 35 to 7 inclusive. It consists of a main body 7 made of sheet metal. Its rear narrow portion is bent upon itself for increasing its strength, the end being rounded and provided with a hole 29 for the screw 6. The enlarged overhanging portion 40 30 is adapted to support the cutting blade 23 and has a recess 31 for the cutting edge of the blade, the other edge being tapered as shown. The blade is guided in its place by a pin 32 fitting into a corresponding hole in the blade. The end of 45 the pin 32 fits into a hole 33 in a clamping plate 34 shown separately in Fig. 7. It is shaped like the portion 30 of the holder and also has a recess 35 for the cutting edge of the blade. The clamping plate is held against the portion 30 of the 50 holder with the blade 23 between them by means of clips 36 and 37 pivotally supported at 38 and 39 respectively on the portion 30 of the holder. The clips have U-shaped cross-section so that they can frictionally engage the sides of the parts 55 30 and 34 as shown in Figs. 4, 5 and 6. The upper edge portion of the part 30 is bent over so as to hold the upper corner or edge of the blade 23.

A pelt or piece of fur 40 may be held in any 60 convenient frame for slitting it by my device, holding the latter in a hand, but I prefer to use a special stretching frame with a guiding attachment for the box 1. Such a frame is shown in Fig. 8 and consists of a base board 41 supporting 65 a stationary bar 42 on posts 43. The upper side of the bar 42 has a number of sharp pins 44 for holding the pelt 40. The latter is clamped against the bar 42 by a second or clamping bar 46 having holes 47 for the pins 44 and hinged 70 at 48 to the end of the stationary bar 42. The other end of the clamping bar 46 is tightly held against the stationary bar 42 by a hook 49 hinged at 50 to the post 43. The other end of the pelt 40 is held by similar pins 44 on a supporting bar 75 52 and clamped by a bar 53 mounted on a hinge

54 and held by a hook 55. The supporting bar 52 is mounted on posts 56 with tubular portions 57 at the lower ends sliding on rails or guiding bars 58 whose ends are attached to the lower ends of the posts 43. Thumb screws 59 are provided for clamping the posts 56 to the rails 58 in any desired position for stretching the pelt 40. The second bar 52 with its posts 56 may be also attached directly to the base of the machine as by screws or nails if a wide latitude is desired 10 as regards the width of the pelts mounted on the bars.

For large production work several pieces of pelts may be placed one on top of the other and slit simultaneously. It should be noted that 15 the hair of the fur is not damaged by the knives, being readily deflected to the side by the edge of the knife.

My device has an advantage in this respect 20 over ordinary methods, since it is not possible to cut by hand several pelts at once without spoiling the work on account of slippage between the pelts. A single pelt can be slit with my device by hand, holding the pelt against the edge of the table.

More accurate and satisfactory results are obtained when using my device in connection with the pelt supporting frames and, more particularly, with a guiding rail 60 for the box 1 as shown in Figs. 8, 9 and 10. The rail is pivotally 30 supported at 61 on a post 62 having a foot 63 which can be moved along the bar 42. The post 62 has sides tapered at the same angle at which the knives are supported on the box. It is placed with one of its sides against a supporting bar 35 64 mounted at the side of the bar 42 so as to place the rail 60 in a desired angular or perpendicular direction. The bar 64 has a longitudinally extending slot 65 so that it actually consists of two bars separated by the slot 65. The 40 post 63 has T-shaped buttons 66, 66' and 66'' slidably and frictionally sliding in the slot 65 so that the post 62 with the rail 60 can be placed in any position along the bar 64. The post 62 may be tightened or locked in its position by any 45 suitable device such as a set screw, etc.

For supporting the box on the rail 60 it is provided with hooks 67, 68 and 69 extending from the front door of the drawer 2. The hooks are used for suspending the box from the guiding 50 rail 60 with the knives extending downward. The hook 67 is used when the rail extends to the left as shown in Fig. 8, hook 68 is used when the rail 60 is turned to the right, and the middle hook 69 is used when the rail is placed at right 55 angles to the supporting frame, the button 66'' engaging the slot 65, or when the knives are placed perpendicularly to the box, i. e., in position 7', Fig. 1. Only one hook 67 is shown in Fig. 8 for clearness.

The rail 60 is supported in a raised position by a spring 70, the spring being sufficiently strong also to support the weight of the box hanging on the rail by one of the hooks. For bringing the knives in contact with the pelt, the front end 65 of the rail 60 is depressed by hand, and the box is then moved along the rail, the knives slitting the pelt into the corresponding number of narrow strips. The strips are held together by marginal portions of the pelt, these portions being 70 slit afterwards when the strips are being matched and shifted for making a narrow and long piece of fur of each pelt, i. e., for "letting out" or "resetting."

75 A modified device is shown in Fig. 11, the box

1 being provided with a hook or hooks 67 slidably fitted on a rail 74. The latter is movably supported at one end on a pin 75 on a post 76, the other end being slidably supported on a rod 77 extending from a post 78. A spring 79 tends to keep the end of the rail raised as shown. The hook 67 has a lug 80 threaded for a long feed screw 81 operated by an electric or other suitable motor 82 mounted on the end of the rail 74. The 5 knives are brought against the peit 40 by manually depressing a handle 83 on the end of the rail. The motor 82 is started at the same time, the current being closed by contacts 84 operated by a spring 85 on the free end of the rail. The 10 rail can be also operated by a pedal 86 connected to the rail by a rod or cord 87. The latter arrangement can be also used for moving the box 1 on the rail 74. The two posts 76 and 78 can be given any desired angular position on the board 20 41. Lugs or buttons 72, Fig. 11, are provided at the sides of the box 1, limiting its approach to the frame bars 46 and 53.

It is understood that my fur slitting machine can be further modified without departing from the spirit of my invention as set forth in the appended claims.

I claim as my invention:

1. A fur slitting device comprising a base, means to support a piece of fur on the base in a stretched position, a rail, means to support the rail at an elevation above the fur at a small angle to the base, an elongated member, a hook at the upper side of the elongated member having flat sides at a sharp angle to the member, the hook 30 slidably engaging the rail so as to hold the elongated member in a fixed angular position to the rail, and a plurality of knives mounted on the elongated member side by side in a parallel relation to each other and to the rail, the knives being adapted to be moved on the rail and to cut the fur into a plurality of parallel narrow strips on a bias to the edge of the fur.

2. A fur slitting device comprising a base, means to support a piece of fur on the base in a stretched position, a rail, means including a rear post for supporting the rail on the base at an elevation above the fur, an elongated member 45 slidably supported on the rail for movement in a fixed angular relationship thereto, a plurality of knives spaced in parallel relation to each other and to the rail, the knives being adapted to cut the fur into parallel strips when the elongated member is moved on the rail, guiding bars on the base, and means to support the post in a slidably adjustable position on the guiding bars in a fixed angular position.

3. A fur slitting device comprising a base, means to support a piece of fur on the base in a stretched position, a rail, means including a rear 50 post for supporting the rail on the base at an elevation above the fur, an elongated member slidably supported on the rail for movement in a fixed angular relationship thereto, a plurality of knives spaced in parallel relation to each other and to the rail, the knives being adapted to cut the fur into parallel strips when the elongated member is moved on the rail, guiding bars on the base, and means to support the post in a slidably adjustable position on the guiding bars in one of the three fixed angular positions.

4. A fur slitting device comprising a base, means to support a piece of fur on the base in a stretched position, a rail, means including a rear post for supporting the rail on the base at an elevation above the fur, an elongated member 55

slidably supported on the rail for movement in a fixed angular relationship thereto, a plurality of knives spaced in parallel relation to each other and to the rail, the knives being adapted to cut the fur into parallel strips when the elongated member is moved on the rail, guiding bars on the base, the post having three sides at an angle to each other, and projections on the sides slidably engaging the guiding member for supporting the rail in one of three fixed angular positions. 10

5. A fur slitting device comprising a base, means to support a piece of fur on the base in a stretched position, a rail, means to support the rail at an elevation above the fur, an elongated member, a hook at the upper side of the elongated member adapted to slidably engage the rail and to hold the elongated member in a fixed angular position in relation to the rail, a plurality of sharp-pointed knives having straight narrow shanks, means to removably support the shanks 20 on the elongated member in a spaced parallel relation to each other and in one of three fixed angular positions to the elongated member the main portion of the knives being offset downward below the elongated member, the knives 25 being adapted to cut the fur into strips when the member is moved on the rail.

6. A knife blade holder for a fur slitting device comprising a holding member made of sheet metal having a wide front portion, means to support a cutting blade on the front portion, an elongated straight narrow rear portion offset in relation to the front portion, and means on the end of the rear portion for supporting the holder 30 on the fur slitting device. 35

7. A fur slitting device comprising a base, a clamping bar on the base for holding one side of a piece of fur, means to support the other edge of the fur, a guiding rail, means to support the rail on the base at an elevation above the bar and at a small angle thereto, an elongated member 40 slidably supported on the rail in a parallel relation to the clamping bar, and a plurality of knives on the elongated member supported in a parallel relation to the rail and adapted to slit the fur into strips when the elongated member is moved on the rail. 45

8. A fur slitting device comprising a base, a clamping bar on the base for holding one side of a piece of fur, means to support the other edge 50 of the fur, a guiding rail, means to support the rail on the base at an elevation above the bar in one of three positions at different angles to the bar, an elongated member, adjustable means to slidably support the member on the rail in a position parallel to the bar, and a plurality of knives removably and adjustably supported on the member in a position parallel to the clamping bar. 55

9. A fur slitting device comprising a base, a clamping bar on the base for holding one side of a piece of fur, means to support the other edge of the fur, a guiding rail, means to support the rail on the base at an elevation above the bar in one of three angular positions to the clamping bar including right and left positions at approximately 15° and one position at right angles, an elongated member, adjustable means to slidably support the member on the rail in a position parallel to the bar, and a plurality of knives removably and adjustably supported on the member in a position parallel to the clamping bar. 60 65

10. A fur slitting device comprising a base, a clamping bar on the base for holding one side of a piece of fur, means to support the other edge 70 75

of the fur, a plate in front of the clamping bar, a plurality of sharp pins on the plate positioned in two rows at small right and left angles to the clamping bar and adapted to support the fur, a 5 guiding rail, means to support the rail on the base at an elevation above the plate selectively in one of the two positions corresponding to one of the rows of the pins, an elongated member 10 slidably supported on the rail in a parallel relation to the base, and a plurality of knives on the elongated member parallel to each other and to the rail, adapted to cut the fur into strips when the member is moved on the rail.

11. A fur slitting device comprising a base, a 15 clamping bar on the base for holding one side

of a piece of fur, means to support the other edge of the fur, a guiding rail, means to support the rail on the base at an elevation above the bar, a plurality of knives having straight shanks, pins extending from the ends of the shanks, the elongated member having a row of holes for the pins, the knives being adapted to be rotated on the pins for placing them in one of the three positions corresponding to the three positions of the rail, and means to clamp the knives in one of the selected positions on the elongated member, the knives being adapted to slit the fur into parallel strips when the elongated member is moved on the rail. 5 10

SAMUEL DEUTSCHER. 15
